TIMING APPARATUS

Robert Steeneck, New York, N. Y., assignor to The Western Union Telegraph Company, New York, N. Y., a corporation of New York

Application October 2, 1937, Serial No. 166,981

14 Claims. (Cl. 161—17)

This invention relates primarily to timing apparatus and more particularly to apparatus of this nature adapted for use in timing athletic games or contests of skill and endurance, such as 5 for example, some of the events of a rodeo and like events.

In certain athletic events or contests, such as for example those wherein the winner or victor is the contestant able to perform a certain 10 feet in the shortest length of time or endure certain hardships for a predetermined length of time, it is desirable that these times be determined with the maximum possible accuracy. The accuracy of the timing is especially important 15 where the contestants perform one after the other and each must be separately timed and the winner determined from these separate times. Such a condition prevails in the riding event of a rodeo where the rider able to properly ride 20 certain horses the longest time is the winner.

Heretofore, these timing operations were usually performed by one or more timekeepers using stop-watches or like instruments, the results usually being manually posted on a board or 25 announced for the benefit of the contestants and spectators. Obviously, such methods had many disadvantages likely to result in inaccuracies and also the spectators were unaware of the progress of the official time during the event 30 they were witnessing and it was not known to them until after the termination of the event.

It is, therefore, the general object of this invention to provide a large dial clock, or a plurality thereof operating in synchronism, visible 35 to the spectators of an event and controlled by an official timekeeper, which is particularly adapted for use in timing events or contests such as those present in a rodeo.

Another object of the invention is to provide 40 a clock of the above type, the hand or hands of which may be quickly reset to the zero or starting position.

These and other more specific objects of the invention defined by the terms of the appended 45 claims will be apparent from the following detailed description of the invention.

In large dial clocks wherein the hand or hands are driven through gear trains comprising several gears, there is likely to be considerable play or 50 lost motion between the driving source and the hand or hands. Such a condition is particularly noticeable at the starting of the clock.

Therefore, in accordance with the present invention, there is provided means normally tending 55 to rotate the hand of the clock in a reverse

direction whereby the play and lost motion in the gears is eliminated at the hand of the clock. Means is provided for resetting the hand of the clock by rotating the same in a reverse direction at a comparatively high rate of speed, to a position slightly ahead of the zero position, relative to the normal direction of rotation, and then rotating the hand at its normal speed of rotation to the zero position, at which point it is automatically brought to rest. 5

Another feature of the invention is the employment of a planetary gear system in driving the hand of the clock in one direction and returning the hand of the clock to a zero position at a higher rate of speed by releasing one member of 10 15 the planetary gear system.

In the preferred embodiment of the invention a constantly rotating synchronous motor is employed for furnishing the driving force of the clock. A planetary gear system and a reduction 20 gear box is employed to rotate the clock hand at the desired speed. An electromagnetic clutch operable from a remote point couples and uncouples a motor to the clock hand. The reset of the clock hand to a normal position is controlled 25 from a reset switch and its operation causes the release of a member of the planetary gear system enabling the hand to rotate in a reverse direction at a high rate of speed. On the reset operation the hand is rotated a slight amount past 30 the zero position and then at its normal speed to the zero position where it is automatically stopped ready for the release in timing the next event. 35

A more complete understanding of the invention may be had from the following detailed description thereof taken in conjunction with the accompanying drawings, in which:

Fig. 1 is an elevational view of the clock face or dial indicating device controlled by the present invention; 40

Fig. 2 is a plan view of the driving and control mechanism of the clock;

Fig. 3 is a partial sectional view taken on line 3—3 of Fig. 2; 45

Fig. 4 is a partial sectional view taken on line 4—4 of Fig. 2;

Fig. 5 is a partial sectional view taken on line 5—5 of Fig. 4;

Fig. 6 is a partial sectional view taken on line 6—6 of Fig. 2; and 50

Fig. 7 is a diagrammatic view of the electrical circuits and the relationship of certain of the mechanical parts and the controls therefor employed in the clock. 55

Referring first to Fig. 1 which shows an elevational view of the clock face 11 preferably employed with this invention, a single hand 12 is adapted to rotate about a point at the center of the clock face. The clock face 11 is divided into sixty divisions such as 13 and the end of the hand 12 cooperates therewith to indicate elapsed time, as will be hereinafter described. The clock face 11 and hand 12 are preferably of such a size as to be clearly visible to all the spectators and players, but where this is impracticable, a plurality of adjacent or remotely disposed clock faces may be employed, the indicating elements being operated by a common means, or remotely disposed means operating in unison and controlled from the common means, as will be apparent from the following description.

A horizontal base or mounting plate 14, Fig. 2, has mounted at the rear thereof a constantly rotating motor M which may be a synchronous motor driven from a well regulated alternating current supply or any other type motor operated at a substantially constant speed by governors or speed controlling devices well known in the art. A worm gear 16 attached to one end of the motor shaft meshes with another gear 17 located directly therebelow. The gear 17 is fixed for rotation therewith by a set screw 18 to a shaft 19, the shaft 19 being suitably pivoted at one end in a post 21 and at the other end in a gear box 22. Also fixed to the shaft 19 for rotation therewith by a set screw 23 is a collar 24 which comprises a driving member of an electro-magnetically controlled grab clutch of the type well known in the art and indicated in general by reference numeral 25, Figs. 2 and 4. The driven member of the grab clutch 25 comprises a flanged sleeve 26 loosely mounted on the shaft 19 with teeth thereupon in operative relation with similar teeth on the driving member 24. The sleeve 26 is at all times operatively engaged with another sleeve 27 free on the shaft 19, by means of interengaging tongues and grooves 28. A spring 29 coiled about the tongues and grooves of the sleeves 26 and 27 normally tends to slide the sleeve 26 to the right, as shown in Fig. 4, to bring its teeth into engagement with the teeth on the constantly rotating collar 24. However, the upper end of a lever 31 normally engages a side cam surface 30 on the sleeve 26 to hold it to the left and its teeth out of engagement with the teeth on the collar 24. The lever 31 is pivotally mounted at its lower end on a rod 32 and has fixed thereto an armature 33. The armature 33 is in operative relation with the pole pieces of a so-called clutch magnet 34. When the magnet 34 is energized, the lever 31 is caused to pivot and withdraw the upper end thereof from out of engagement with the side cam surface 30 of the sleeve 26, Fig. 5, whereupon the spring 29 slides the sleeve 26 to the right, Fig. 4, engaging its teeth with the teeth of the collar 24 and thus the sleeves 26 and 27 rotate with the shaft 19. When the magnet 34 is deenergized, the upper end of the lever 31 falls back upon the sleeve 26 in the path of the side cam surface 30 and as the sleeve 26 continues to rotate, the upper end of the lever 31 and the side cam surface 30 engage and cam the sleeve to the left. This causes the disengagement of the teeth thereon with the teeth on the collar 24 and a further projection of the side cam surface at right angles to the direction of rotation of the sleeve then engages the top of the lever 31 and brings the sleeve to rest in a normal stop position. In this manner the clutch

magnet 34 controls the operation of the clutch 25.

A cam-shaped flange 36, Fig. 5, on the sleeve 27 has in engagement with the periphery thereof a cam follower 37. The cam follower 37 is mounted at the right end of a lever 38 pivoted at its center on a shoulder screw 39 extending horizontally from a plate 41 attached to the side of the gear box 22. A spring 42 holds the cam follower 37 in engagement with the cam 36, and the two elements 37 and 36 cooperate with one another to prevent rotation of the sleeve 27 in a reverse direction due to its sudden stop by the lever 31.

The sleeve 27 comprises the input member to the gear box 22 and the shaft 43, Figs. 2 and 4, the output member thereof. The gears 16 and 17, and the speed of the motor are so arranged that the shaft 19 rotates at a speed of 300 R. P. M., and as the clutch 25 is capable of stopping the sleeve 27 during any revolution thereof, the clock mechanism hereinafter described can be stopped in a time interval equal to one-fifth of a second or less. The gear box 22 is capable of a speed reduction of twenty-five to one and therefore the shaft 43 is capable of rotating at a speed of 12 R. P. M. The forward end of the shaft 43 is pivotally supported in a sleeve 44 which in turn is pivotally supported in a bearing block 46 attached to the forward end of the base plate 14. The hand 12 is attached to the forward end of the sleeve 44 and is adapted to normally rotate at a speed of 1 R. P. M. by means of a planetary gear unit indicated in general by reference numeral 47 and hereinafter described.

Pinned to the shaft 43 for rotation therewith by a pin 48 is a gear 49 which has twenty-four teeth thereon and meshes with a plurality of gears, such as 51, each having thirty-six teeth. The gears 51 are pinned to associated gears 52 for rotation together by pins, such as 53, and each pair of gears 51 and 52 is loosely mounted on associated studs 54. The studs 54 are parallel to the shaft 43 and are carried by a collar 56 loosely mounted on the shaft 43. The gears 52 have twenty teeth thereon and each meshes with another gear 57 having forty teeth which is loosely mounted on the shaft 43. Pinned to the gear 51 by pins such as 58 for rotation therewith is a twenty-four tooth gear 59 also loosely mounted on the shaft 43. The gear 59 meshes with thirty-six tooth gears 61 loosely mounted at the left hand end of the studs 54 which in turn mesh with a ninety-six tooth sun gear 62. The sun gear 62 is attached by screws 63 to the flange 64 forming a part of the sleeve 44. As apparent to those versed in the art from the size of the gears described comprising the planetary unit and their arrangement, it is evident that by holding the collar 56 stationary, as herein-after described, and rotating the shaft 43 at a speed of 12 R. P. M., the sleeve 44 will rotate at a speed of 1 R. P. M. in an opposite direction. As viewed from the face of the block the shaft 43 is adapted to rotate at a speed of 12 R. P. M. in a counter-clockwise direction, and the sleeve 44 at a speed of 1 R. P. M. in a clockwise direction, although it will be apparent that this particular speed differential is not essential to the invention.

Attached by screws, such as 66, to the shaft 43 for rotation therewith, at the right of the planetary gear unit 47, Fig. 4, is a flanged collar 67. A plate 68 slidably mounted on the shaft 43 is adapted to rotate with the collar 67 by means of interengaging tongue and grooves 70, 75

Fig. 1. A coiled spring 69 between a flange on the collar 67 and the plate 68 exerts an axial force on the plate 68 to keep it and a friction disc 71, such as a felt washer, in frictional engagement with the right hand face of the collar 56, thereby tending to rotate the collar 56 with the shaft 43 for purposes hereinafter apparent. However, the collar 56 is normally held from rotation as hereinafter described. Attached to the forward end of the shaft 43 for rotation therewith is a collar 72 adjacent a collar 73 slidably mounted on the shaft and operatively associated therewith by means of interengaging tongues and grooves 75. A coiled spring 74 disposed between flanges on the two collars 72 and 73 holds a friction element, such as 76, Fig. 4, against a plate 77 which, together with the hand 12, is fixed by screws, such as 78, for rotation therewith to the front end of the sleeve 44. Thus the hand tends to rotate in a counter-clockwise direction with the shaft 43. The primary purpose of the friction element 76 is to put a slight load on the hand 12 to prevent it from vibrating or jumping due to play or lost motion in the gears. Attached by screws, such as 79, Figs. 4 and 6, is a ring 81 which has in the periphery thereof a series of notches such as 82. Normally engaged in one of the notches of the ring 81 is the upper horizontal end 83 of a lever 84. The lever 84 is pivoted at its lower end on a pin 86 and is adapted to be pivoted within certain limits by a reset magnet 81. With the end of the lever 84 engaged in a notch in the ring 81, the collar 56 is held from rotation, and for such condition, as hereinbefore described, the hand 12 will rotate in a clockwise direction at a speed of 1 R. P. M. when the clutch 25 is operated.

The manner in which the clock is controlled by the timekeeper or official will now be described. Referring to Fig. 7, four switches, viz., a ten second switch 88, an eight second switch 89, a start switch 91 and a reset switch 92, all having a normal unoperated position to the left and operated positions to the right, control all functions of the clock. Let it be assumed that the clock hand 12 is in its normal zero position and it is desired to time an event of some unpredetermined length such as for example a race. At the start of the event the timekeeper operates the tongues of the start switch 91 to the right, which operation connects a ground through the right hand tongue of the start switch over a conductor 93 and through the coil of the clutch magnet 34 to battery. This causes the energization of the clutch magnet 34 and the operation of the clutch 25 whereupon the hand 12 commences to rotate at a speed of 1 R. P. M. as hereinbefore described and continues to do so as long as the switch 91 remains operated. At the termination of the event the timekeeper operates the start switch 91 to the left to open a circuit to the start magnet 34 whereupon the clutch 25 is disengaged and the hand 12 brought to rest in such a position as to indicate the elapsed time during the event. Thus a continuous event is timed and it is evident from the circuits that in timing an event likely to have rest or time-out periods therein, the operation of the switch 91 to a normal position halts the progress of the hand 12 during the time-out periods.

Assume that the clock hand is in its normal zero position and it is desired to indicate the elapse of a predetermined length of time such as an eight or ten second interval. For such a condition the timekeeper operates either one or

the other of the switches 88 or 89 to the right, which operation completes a circuit from ground at the right hand tongue of a normally unoperated relay 94, over a conductor 96, through the center tongue of the operated one of the switches 88 or 89, over conductor 93 and through the coil of the clutch magnet 34 to battery. This circuit causes the operation of the clutch 25 and initiates the rotation of the clock in the same manner as the operation of the start switch 91 and the manner in which an eight second or ten second interval is terminated and indicated by the clock will now be described. Attached to the collar 64 by the screw 63 are two contact actuating members 97 and 98, Figs. 2 and 3. These members 97 and 98 are in operative alignment with associated contacts 99 and 101, respectively, and as the collar 64 rotates predetermined amounts the contacts 99 and 101 are closed. The collar 64 and the hand 12 as hereinbefore described, rotate together and the contact actuating members 97 and 98 are so arranged as to close their associated contacts 99 and 101 when the hand 12 has rotated eight and ten seconds from its normal zero position. If the eight second switch 89 was moved to the right to initiate the operation of the clock, then after the clock has been in operation eight seconds, the member 98 closes the contact 101. This completes a circuit from ground at the contact 101, Fig. 7, over conductor 102 through the right hand tongue of switch 89, over a conductor 103 and thence through the coil of the relay 94 to battery. This causes the energization of the relay 94 whereupon its right hand tongue opens the circuit hereinbefore described to the clutch magnet 34 to cause the deenergization of the clutch magnet 34 and stop the operation of the clock. The energization of the relay 94 also causes its left hand tongue to complete a circuit from battery to an alarm or signalling mechanism such as 104, to ground, which thereupon operates and signals the contestants and spectators the termination of an eight second interval. Normally the alarm 104 continues to operate until the operated switch 89 is returned to its normal left hand position. In the same manner a ten second interval may be indicated by closing the ten second switch 88. Obviously, with the embodiment shown any interval up to one minute could be indicated by changing the location of the contacting members such as 97 and 98 relative to their associated contacts, 99 and 101.

The manner in which the clock hand 12 is returned or reset from some intermediate point to its zero or normal position will now be described. This function is controlled by the reset switch 92 and with the clock hand in any position other than its normal position and with the switches 88, 89 and 91 all to the left, the operation of the switch 92 completes the following circuits; first, from ground at the left hand tongue of the switch 88, through the left hand tongue of the switch 89, through the left hand tongue of switch 91, switch 92, over a conductor 106 and through the coil of the reset magnet 87 to battery; second, through the switches 88, 89, 91 and 92 as described over conductor 108, through the coil of a relay 109 and thence through one or the other or both of contacts 111 and 112 connected in parallel to battery. The ground for the reset switch 92 passes through the switches 88, 89 and 91 so as to prevent a reset operation with any of these switches in an operated position for obvious reasons. These circuits cause

the energization of the magnet 87 and the relay 109 which are locked in their energized position by the ground at the tongue of relay 109. As the magnet 87 operates to withdraw the end of the lever 84 from a notch in the disc 81, a projection 113 on the lever 84 causes a contact 114 to be closed. One side of the contact 114 is grounded and its closing applies ground over a conductor 116 through the clutch magnet 34 to battery, 10 causing the clutch 25 to operate.

As heretofore described, the operation of the clutch causes the shaft 43 to rotate at a speed of 12 R. P. M. and with the end 83 of the lever 84 not engaged in a notch 82 in the disc 81, the 15 complete planetary unit 47 and the hand 12 is allowed to rotate in a counterclockwise direction with the shaft 43 through the action of the friction members 71 and 76, hereinbefore described. The planetary unit 47 and the hand 12 will continue to rotate in a counterclockwise direction 20 with the shaft 43 to bring a lug 117, Figs. 2, 3 and 7, secured to the collar 64, into engagement with a horizontal arm of a bell crank 118. The bell crank 118 is pivotally supported on a pivot rod 25 119 in a bracket 121 suitably supported from the base plate 14. The lug 117 engaging the bell crank 118 causes it to pivot and the depending arm 122 thereof closes a contact 123 and opens the contact 111. The closing of the contact 123 30 maintains a ground to the clutch magnet 34 to maintain the clutch operated for reasons hereinafter apparent. After the lug 117 has pivoted the bell crank 118 a predetermined amount, the horizontal arm thereof engages the bracket 121 35 to stop further pivoting thereof, which in turn prevents further rotation of the collar 64 and the hand 12, and at such a time the hand 12 is slightly ahead of its zero rest position at approximately the position indicated by the dot-dashed outline 40 thereof in Fig. 1. However, the collar 56 and disc 81 of the planetary unit continue to rotate with the shaft 43 until stopped as hereinafter described. A series of pins or screws such as 124, arranged around the periphery of the collar 56 45 cooperates with the tongue of the contact 112 to open the contact only when the upper end of the lever 84 is approximately at the midpoint between two adjacent notches 82 of the disc 81. If the bell crank 118 happens to open the contact 111 at the same time one of the screws opens 50 the contact 112, the circuit to the relay 109 will be opened which in turn opens the circuit to the reset magnet 87. Thereupon the lever 84 will be released and the upper end thereof engages the periphery of the disc 81 at approximately the 55 midpoint between two adjacent notches 82. The deenergization of the relay 109 and the magnet 87 at this time does not break the circuit to the clutch magnet 34 as this circuit is maintained 60 through the closed contact 123. Therefore, the disc 81 continues to rotate with the shaft 43 until the end of the lever 84 drops in a notch 82 in the disc 81. As hereinbefore described with the disc 81 held from rotating by the lever 84 and the clutch 25 operated, the collar 64 and the hand 12 will rotate in a clockwise direction at a speed 65 of 1 R. P. M. This condition continues until the lug 117 rotating with the collar 64 allows the bell crank 118 to pivot to its normal position and the contact 123 open the circuit to the clutch magnet 34 which stops the clock with the hand 12 in exactly its zero or normal stop position. When 70 the contact 112 is not open at the time the bell crank 118 opens contact 111, the reset magnet 87 75 is maintained energized until the end of the lever

84 is between two notches in the disc 81 whereupon one of the screws 124 causes contact 112 to open. This, as described, allows the end of the lever 84 to engage the periphery of the disc 81 and enter the next notch 82. In this manner the 5 contact 112 prevents the reset magnet 87 from being deenergized at any time other than when the end of the lever 84 is between two notches on the disc 81. Otherwise a slight bounce of the lug 117 when engaging the bell crank 118 would 10 be likely to permit the end of the lever 84 to stop the disc 81 and the clutch magnet to become deenergized all at the same time. This would be likely to result in the clock being stopped with the hand 12 in some other than its true zero position. It has been found that with the clutch such as 25 capable of operating in one-fifth of a second, and with twenty-five notches in a disc 81, the hand 12 will always be brought to rest in its true zero position. By rotating the hand of the 20 clock a few degrees to a position ahead of its normal zero position and then rotating it at its normal speed of rotation to the zero position, as described, all the play and lost motion in the gears may be taken up. Therefore, when the 25 clock is again started, no time will be consumed in taking up the play in the gears.

Although the clock is designed primarily for timing and indicating events and intervals of one minute or less, it is obvious that with events 30 of greater length the hand 12 will make more than one complete revolution. The spectators can easily remember the number of revolutions of the hand in timing events up to about three minutes but for events of greater length another 35 hand rotatable at the proper speed or a dial indicator could easily be provided to indicate the number of minutes or revolutions of the hand 12 which would be reset at the same time.

It is obvious, of course, that various other modifications of the apparatus shown and described herein may be made without departing from the spirit or essential attributes of the invention, and it is desired, therefore, that only such limitations shall be placed thereon as are imposed 40 by the prior art or are specifically set forth in the appended claims.

What is claimed is:

1. In a timing apparatus for measuring variable time intervals, a movable time measuring indicator having a normal position, means for moving said indicator from said normal position in one direction at a predetermined time measuring speed to an off-normal position, means for moving said indicator from said off-normal position 50 in the opposite direction and at a second predetermined speed through said normal position to a predetermined position in advance of said normal position, means for halting said indicator in said predetermined position for at least a predetermined length of time, means for moving said indicator from said predetermined advanced position at said time measuring speed and direction to said normal position, and means for stopping said indicator in said normal position. 55

2. In a timing apparatus for measuring variable time intervals, a movable time measuring indicator having a normal position, a first manually operable means for controlling the movement of said indicator in one direction from said normal position and at a predetermined time measuring speed to an off-normal position, a second manually operable means for initiating the automatic resetting of said indicator to said normal position, and means operable in the resetting of said indi- 60 65 70 75 80 85 90 95 98 99 100

cator for moving the same at a second predetermined speed in a direction opposite to time measuring direction to a position ahead of said normal position and thereafter at said time measuring speed and direction to said normal position and stopping the same thereat.

5. In a game timing apparatus for indicating accumulated increments of time, a rotatable time measuring indicator having a normal position, a driving means for said indicator, a first means embodying said driving means for rotating said indicator at a predetermined time measuring speed in one direction during consecutive time increments from said normal position to any one 10 of a plurality of off-normal positions, a second means embodying said driving means for rotating said indicator at a second predetermined speed and in the opposite direction to said time measuring direction from any one of said off-normal 15 positions through said normal position to a predetermined position in advance of said normal position and means automatically operative within predetermined time limits after the rotation of said indicator to said predetermined position for 20 enabling said first means to rotate said indicator 25 to said normal position.

4. In a game timing apparatus, a time measuring indicator having a normal position, means for moving said indicator in one direction from a 30 normal position at a predetermined speed to indicate accumulated increments of time, means for continuously moving said indicator at a second predetermined speed in opposite direction to said time indicating direction an amount equal to said 35 time indicating movement plus a predetermined amount and means automatically operative thereafter for moving said indicator at said time indicating speed and direction to said normal position.

5. In a game timing apparatus, a time measuring indicator having a normal position, means for rotating said indicator from said normal position to an off-normal position to indicate accumulated increments of time in a predetermined direction and at a predetermined speed, 40 means for continuously rotating said indicator from said off-normal position in the opposite direction at a second predetermined speed an amount equal to the rotation in said time indicating direction less the complete revolutions thereof plus a predetermined amount, means for automatically stopping said indicator for at least a predetermined length of time thereafter and means for automatically rotating said indicator 45 at said time indicating speed to said normal position and bringing to a stop thereat.

6. In a game timing apparatus, a time measuring indicator having a normal position, means for rotating said indicator from said normal position to an off-normal position to indicate accumulated increments of time in a predetermined direction and at a predetermined speed, means for continuously rotating said indicator from said off-normal position in the opposite direction at a second predetermined speed an amount equal to the rotation in said time indicating direction less the complete revolutions thereof plus a predetermined amount, and means for automatically rotating said indicator at said 50 time indicating speed to said normal position and bringing to a stop thereat, said means operating in the order named.

7. In a timing apparatus, a time measuring indicator movable from a normal position to indicate accumulated increments of time, a

normally operating driving means, a planetary gear unit disposed between said indicator and said driving means for moving said indicator in one direction at a predetermined speed, means for releasing a normally stationary member of 5 said planetary unit and means operative on the release of said normally stationary member for moving said time indicator in the opposite direction to said time indicating direction.

8. In a timing apparatus, a time measuring indicator movable from a normal position to indicate accumulated increments of time, a normally operating driving means, a planetary gear unit disposed between said indicator and said driving means for moving said indicator in one direction 10 at a predetermined speed, means for releasing a normally stationary member of said planetary unit, means operative on the release of said normally stationary member for moving said time indicator in the opposite direction to said time 15 indicating direction at a higher predetermined speed to a position ahead of said normal position relative to said time indicating direction of motion, means automatically operative thereafter for reengaging said normally stationary 20 member, moving said indicator at said time indicating speed and direction to said normal position and bringing to a stop thereat.

9. In a timing apparatus, a time measuring indicator movable from a normal position to indicate accumulated increments of time, a normally operating driving means, a clutch and a planetary gear unit disposed between said indicator and said driving means, means for controlling said clutch to clutch said indicator to said driving means to move said indicator in one direction at a predetermined speed, means for releasing a normally stationary element of said planetary gear unit, means for simultaneously operating said clutch and releasing said normally stationary 30 element, means operative thereafter to move said indicator at a second predetermined speed in a direction opposite to said time indicating direction.

10. In a timing apparatus, a time measuring indicator movable from a normal position to indicate accumulated increments of time, a normally operating driving means, means comprising a planetary gear unit disposed between said indicator and said driving means for driving said indicator at a predetermined speed in a time indicating direction and a second means comprising said planetary gear unit for resetting said indicator to said normal position and means whereby said reset operation comprises moving 40 said indicator in a direction opposite to said time indicating direction a variable amount greater than said time indicating movement and then a predetermined amount in said time indicating direction.

11. In a timing apparatus, a time measuring indicator movable from a normal position to indicate accumulated increments of time, a normally operating driving means, means comprising a clutch for positively clutching said driving means to said indicator to move the same in a time indicating direction at a predetermined time indicating speed, frictional means associated with said indicator and driven from said driving means tending to move said indicator in an opposite resetting direction at a second predetermined speed during movement thereof in said time indicating direction and means for disabling said means driving said indicator in said time indicating direction.

cating direction and allowing said friction means to move said indicator in said resetting direction.

12. In a timing apparatus, a time measuring indicator movable from a normal position to indicate accumulated increments of time, a normally operating driving means, means comprising a gear reduction unit having an appreciable amount of backlash in the gears thereof for driving said indicator in one direction at a predetermined time 10 indicating speed, frictional means driven from said driving means tending to drive said indicator in a direction opposite to said time indicating direction during movement thereof in said time indicating direction, means including said frictional means for invariably resetting said indicator to said normal position in a direction opposite to said time indicating direction and at a second predetermined speed and means for taking up the backlash in said gears during said 20 resetting operation.

13. In a timing apparatus, a rotatable time measuring indicator having a normal position,

means for rotating said indicator from said normal position at a normal time measuring speed to any one of a plurality of off-normal positions, means for arresting the normal time measuring motion of said indicator, means for 5 rotating said indicator at a faster speed to a position a predetermined distance from said normal position and means automatically operative thereafter for rotating said indicator at said time indicating speed of rotation to said normal 10 position.

14. In a timing apparatus, a single driving means, a time measuring indicator movable from a normal position to indicate elapsed intervals of time, means driven from said single driving 15 means including a planetary gear unit for moving said indicator in a time measuring direction and in a reverse resetting direction and means for bringing said time measuring indicator to rest at its normal position. 20
